DESIGN FOR A DISPLAY TABLE

Robert J. Gunder, Manor Township, Lancaster County, Pa., assignor to Hamilton Watch Company, Lancaster, Pa.

Application February 23, 1940, Serial No. 90,463

Term of patent 14 years

To all whom it may concern:

Be it known that I, Robert J. Gunder, a citizen of the United States, residing in Manor Township, in the county of Lancaster and State of Pennsylvania, have invented a new, original, and ornamental Design for a Display Table, of which the following is a specification, reference being had to the accompanying drawing, forming part thereof.

The figure is a perspective view of a display table showing my new design.

The opposite side of the display table is substantially the same as that shown.

I claim:

The ornamental design for a display table, as shown and described.

ROBERT J. GUENDER.
